UNITED STATES PATENT OFFICE.

MIECISLAW MARCKS, OF LÜBECK, GERMANY.

DENTAL IMPRESSION-CUP.

1,023,213.

Specification of Letters Patent. Patented Apr. 16, 1912.

Application filed June 28, 1911. Serial No. 635,886.

To all whom it may concern:

Be it known that I, MIECISLAW MARCKS, a subject of the Emperor of Germany, residing at Lübeck, in the German Empire, have 5 invented new and useful Improvements in Dental Impression-Cups, of which the following is a specification.

This invention relates to dental impression cups in which the cups are secured together and thus pressed against the palate and the lower jaw-bones of patients, in order to obtain a quick, clean and accurate impression.

The object of the invention is to provide 15 means whereby impressions for dental purposes may be readily and accurately obtained, and the invention consists in certain improvements in construction, which will be fully disclosed in the following specification 20 and claim.

The prevailing practice of pressing an impression cup or mold against each palate or jaw-bone of patients, by means of the fingers, and then making the patient expel the impression is objectionable for the reason, that 25 as soon as the fingers are removed from the cups or molds, the latter are displaced by a movement of the tongue or by other causes, and the bite becomes inaccurate, so that 30 slight defects in the adjustment of the set of teeth constant occur. To obtain an accurate, quick and clean impression and bite it is therefore necessary that the cups or molds lie steadily against the palate and 35 jaw-bone, so that they are not displaced in the act of biting, and are easily removed from the mouth after the impression and bite has been obtained.

In the accompanying drawings, which 40 form part of this specification:—Figure 1 represents a plan view of a pair of impression cups embodying my invention. Fig. 2 is a side elevation, and Fig. 3 is a longitudinal section of the cups in position for 45 taking an impression.

Reference being had to the drawings and the designating characters thereon, *a* *b* indicate cups or molds made of wire or similar

material corresponding to the contour of the jaws, for retaining a suitable wax or other compound and are connected together by means of springs *c* and *d*. Frame *a* for the upper jaw is provided with bars *e* bent to conform to the roof of the mouth and support the wax, while frame *b* for the lower jaw is provided with transverse rods *f* to hold the tongue down so that it cannot move forward and spoil the impression being made. The wax mold for the palate is fastened in frame *a* in such a manner as to 60 make the bars *e* strengthen the palate-plate and press against the roof of the mouth, whereby the lower rounded edge *g* of the mold pushes its way through the frame. The wax mold for the lower jaw-bone is in 65 like manner fastened in frame *b* and the rounded edge *h* pushes its way through the frame. Therenpon the two frames *a* and *b* with the rounded edges *g* and *h* of the molds respectively, are closed upon each other by 70 bending springs *c* and *d*, and are thus put into the mouth of the patient; the molds clinging to the palate and jaw-bone and being kept in that position by the tension of the springs. The impression now obtained 75 is absolutely accurate, and the whole operation an exceedingly simple and clean one. The impression having been obtained, the apparatus is removed from the mouth, and the molds secured in the articulator for the 80 purpose of constructing the set of teeth.

Having thus fully described my invention, what I claim is—

A dental impression cup comprising two oppositely arranged wire frames, the upper frame being provided with bars as *e* and the lower frame with transverse bars *f*, and a spring on each side of and pivotally connected to the frame.

In testimony whereof I have signed my 90 name to this specification in the presence of two subscribing witnesses.

MIECISLAW MARCKS.
